UNITED STATES PATENT OFFICE.

FRED W. LEUTHESSE, OF CHICAGO, ILLINOIS.

DIRECTORY OR NAME BOARD.

SPECIFICATION forming part of Letters Patent No. 731,795, dated June 23, 1903.

Application filed July 28, 1902. Serial No. 117,298. (No model.)

To all whom it may concern:

Be it known that I, FRED W. LEUTHESSE, a citizen of the United States, residing at Chicago, in the county of Cook and State of Illinois, have invented a certain new and useful Improvement in Directory or Name Boards, of which the following is a specification.

This invention relates more particularly to directory or name boards designed or intended for use in buildings and offices for displaying the names of tenants or occupants of the building and for displaying in offices or other places the names of parties and addresses, including also, where required, the telephone-number and other information which is needed by those using the directory or name board.

The invention has for its primary object the construction of a directory or name board in such manner as to enable cards or slips containing the names and other information to be readily inserted in plates and removed when necessary or desired and replaced by another name, including also the feature of readily extending the space or spaces occupied by the names under one letter as may be needed for the insertion of other names under the same letter.

The invention consists in the features of construction and combinations of parts hereinafter described and claimed.

In the drawings, Figure 1 is an elevation showing a complete directory or name board embodying the features of the invention; Fig. 2, a cross-section of the board shown in Fig. 1; Fig. 3, an elevation showing one of the sections of the board for receiving the name cards or strips in one form of construction and showing at the top the manner of inserting the name card or strip by bending the same to insert the ends in the pockets; Fig. 4, a similar view to Fig. 3, showing a portion of one section of the receiver and retainer for the cards or strips with a modified form of construction; Fig. 5, a cross-section on line 5 of Fig. 3; Fig. 6, a cross-section on line 6 of Fig. 3; Fig. 7, a longitudinal section on line 7 of Fig. 3; Fig. 8, a cross-section on line 8 of Fig. 4, and Fig. 9 a cross-section on line 9 of Fig. 4.

The bill-board has a front for receiving and retaining the cards or strips containing the names. This front is made up of a series or

plurality of sections in the arrangement shown. Each section of the front is in the shape of a strip of metal or other suitable material, thin sheet metal being preferred. This strip A has at each side adjacent to its edge a series of receivers or pockets a, which preferably are formed by pressing out a portion of the body, so as to form a receiver or pocket having an opening at its inner edge for the insertion of the end of a name card or strip B into the receiver or pocket, the receiver or pocket having a length, width, and depth sufficient to furnish a space into which the end of the name card or strip fits, as shown in Figs. 3, 5, 6, and 7. It is to be understood that the width of the strip of metal or other material can be varied to suit the length of the name card or strip and the length can be varied to suit the length of the board and the board can consist of a single receiving and retaining sheet or strip or of a plurality of such sheets or strips arranged side by side or otherwise. The construction shown in Figs. 4, 8, and 9 and in the section of the board at the center in Figs. 1 and 2 has, in addition to the receivers or pockets at each side, a loop b, likewise preferably pressed from the body of the sheet or strip under which the name card or strip can be slipped, leaving a space on one side of the loop for the telephone-number or other memoranda and a space on the other side of the loop for the name and address of a party, as shown by the center section of the board in Fig. 1.

The construction of board shown employs a frame C, made of wood or other suitable material and having in its under face a recess c to receive the edges of a backing D, also made of wood or other suitable material, and, as shown, the backing has supporting or uniting strips d, which are necessary where the backing is made up of sections, as would usually be the case. The arrangement shown has between the adjoining edges of the sheets or strips a fastening-strip E, secured, as shown, at the top and bottom by nails or screws e, so as to hold the sections of the front of the board in position within the frame; but other means could be used for securing the sections of the front in place.

The board as a whole is assembled or made up by placing the required number of sec-

tions for the front within the frame and placing in the receivers or pockets of the various sections the name cards or strips, for which purpose one of the name cards or strips can have thereon the letter "A," and another card can have thereon the letter "B," and still another card the letter "C," and so on through the whole alphabet, these cards simply furnishing a guide under which to insert the name cards or strips in alphabetical order. The preferred form of name cards or strips B is one on which the names and other data can be printed by the use of a type-writer, the name cards or strips being sufficiently flexible, so that after the names are printed thereon they can be severally and separately inserted in their proper places in the receivers or pockets of the front of the board and so that they can be readily taken out and replaced by another name card or strip, if necessary, in changing the directory.

The front, made of sheets or strips of thin material and having the receivers or pockets for the ends of the name cards or strips 25 pressed or formed from the body of the metal or other material, can be constructed at little expense, as by means of a suitable die or former a number of the receivers or pockets can be made at a single operation. The receivers or pockets are of a dimension to have the ends of the name cards or strips easily entered thereinto, and when entered the receivers or pockets furnish a retainer by which each name card or strip will be held securely 30 in position, and the receivers or pockets open on the inside and closed on the outside prevent the end withdrawal or slipping of the name card or strip when inserted, and by using a flexible material for the name cards 35 40 or strips the cards or strips can be readily inserted in position or withdrawn therefrom by simply bending the card so that the ends can be slipped into the receivers or pockets and when entered have the receivers or pockets 45 retain the card in position. These several advantages pertain to the directory or name board of my invention and add greatly to the utility of the board, especially in regard to name-spaces, the changing of the name-spaces 50 as to length occupied, and the ready insertion and removal of a card.

What I regard as new, and desire to secure by Letters Patent, is—

1. In a directory or name board, a front made of thin or sheet material and having adjacent to each edge a row of pockets thereon and projecting forwardly therefrom, each pocket open on its inner side and closed on its ends and outer side for the reception and 55 retention of the end of a name card or strip,

the closed outer side of each pocket forming a stop or abutment against endwise movement and displacement of the card or strip when inserted, and the closed ends holding the card in alinement, substantially as described. 65

2. In a directory or name board, a front made of thin or sheet material and having formed therewith or stamped therefrom, adjacent to each side edge, a row of pockets, 70 the pockets projecting forwardly from the face of the front and each pocket open on its inner side and closed on its ends and outer side for the reception and retention of the end of a name card or strip, the closed outer side 75 of each pocket forming a stop or abutment against endwise movement and displacement of the card or strip when inserted, and the closed ends holding the card in alinement, substantially as described. 80

3. In a directory or name board, a front made of thin or sheet material and having formed therewith, or stamped therefrom, adjacent to each side edge, a row of pockets, and also having formed therewith, or stamped 85 therefrom, at one side of the center a row of loops, the pockets and the loops projecting forwardly from the face of the front and each pocket open on its inner side and closed on its ends and outer side, for each pair of pockets 90 to receive and retain the ends of a name card or strip and have the closed outer side of each pocket form a stop or abutment against endwise movement and displacement of the card or strip when inserted, and have the closed 95 ends hold the card or strip in alinement with the loop overlying the card and forming a division of the card or strip on each side of the loop, substantially as described.

4. In a directory or name board, the combination of a front formed of strips of thin or sheet material, each strip having formed therewith, or stamped therefrom, adjacent to each side edge, a row of pockets, each pocket open on its inner side and closed on its ends and outer side, name cards or strips of flexible material entered at their ends into the pockets for the closed outer side of each pocket to form a stop or abutment against endwise movements and displacement of the card or 100 strip when inserted and for the closed ends to hold the card in alinement, a backing for the front, and an inclosing frame surrounding the front and the backing, substantially as described. 105
